DOORLOCK

Application filed July 14, 1932. Serial No. 622,556.

The present invention relates to a lock particularly for revolving doors in banks, jewelry stores and other establishments and has for its primary object to provide, in a manner as hereinafter set forth, a lock which is electrically actuated and controlled from remote points for frustrating attempts at robberies by hold-ups or other methods.

Another important object of the invention is to provide a door lock of the aforementioned character which, in operative or locked position, can only be released by persons at a predetermined remote location, such as a police station, etc.

Other objects of the invention are to provide a door lock of the character described which will be simple in construction, strong, durable, efficient and reliable in operation and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation, showing a lock constructed in accordance with this invention in operative or locked position.

Figure 2 is a view in vertical section, taken substantially on the line 2-2 of Figure 1, showing the locking clutches or elements in inoperative position.

Figure 3 is a view in horizontal section, taken substantially on the line 3-3 of Figure 1.

Figure 4 is a detail view in perspective, showing the cam actuated arms which shift the rod which controls the electric motor switches.

Figure 5 is a view in front elevation of the motor and certain portions of the adja-

cent mechanism and showing, diagrammatically, the electric circuit.

Referring now to the drawings, in detail, it will be seen that the reference numeral 1 designates an upper portion of a revolving door and 2 is a suitable support located horizontally above said door. Embodied in the door 1 and rising therefrom through the support 2 is a shaft 3 on which is splined or slidably keyed, as at B, a double clutch 4. The clutch 4 is provided with with an annular groove 5.

The reference numeral 6 designates an angular bracket having its lower end secured to the support 2 and its upper end supported to another supporting plate 7. At an intermediate point, the bracket 6 is provided with an opening through which the upper end portion of the shaft 3 rotatably extends. Fixed on the bracket 6 and encircling the shaft 3 is a sleeve 8 on which is splined or slidably keyed, as at C, a clutch 9 having an annular groove 10 therein of less width than the groove 5 in the clutch 4. The clutch 9 is operatively engageable with the upper end of the clutch 4. A clutch 11 is fixed on the support 2 and encircles the shaft 3, said clutch 11 being operatively engageable by the lower end of the clutch 4.

The reference numeral 12 designates a vertically slidable shaft which is operatively connected to the clutches 4 and 9 by yokes 13 and 14, respectively. The yokes 13 and 14 are engaged in the grooves 5 and 10, respectively. Also secured on the shaft 12 is a laterally projecting arm 15, the purpose of which will be presently set forth.

An electric motor mounted on the support 2 is designated by the reference numeral 16. The shaft 17 of the motor 16 has fixed on its free end portion a cam 18 which is engaged with the arm 15 for shifting the shaft 12 upwardly in a manner to raise the clutches 4 and 9 to inoperative position, as illustrated in Figure 2 of the drawings. By reason of

the fact that the groove 10 is of less width than the groove 5, the clutch member 9 will be disengaged from the clutch member 4 before said clutch member 4 is disengaged from 5 the clutch member 11.

Located on the support 2 adjacent opposite sides of the electric motor 16 are motor control switches 19 and 20 which are preferably of the toggle or lever type. When 10 the switches 19 and 20 are in the positions shown in Figure 5 of the drawings, the switch 19 is open and the switch 20 is closed. A horizontal rod 21 is slidably mounted in bearings 22 which are provided therefor and 15 said rod 21 extends above the motor shaft 17 and has its ends adjacent the switches 19 and 20. The shaft 21 is operatively connected to the switches 19 and 20 through the medium of yokes 23 which are fixed on the end 20 portions of said shaft. It will thus be seen that when the shaft 21 is shifted in one direction, the switch 19 will be opened and the switch 20 will be closed and when said shaft 21 is shifted in the opposite direction, the 25 switch 19 will be closed and the switch 20 will be opened.

Depending from spaced points on the shaft 21 are arms 24 and 25 between the lower ends of which extend a connecting rod 26. The 30 arms 24 and 25 are operatively engageable by a cam 27 which is fixed on the motor shaft 17 between the motor 16 and the cam 18.

A manually operable switch 28, preferably of the push button type, is interposed in the 35 electric circuit between the switch 19 and the source of current supply. Any desired number of the switches 28 may be provided at suitable points in the bank or other establishment. The switch 28 is normally open. 40 Also interposed in the electric circuit to the switch 19 is an electric signal in the form of a bell 29. Of course, any other form of electric signal may be provided.

Interposed in the electric circuit between 45 the switch 20 and the source of current supply is a normally open switch 30 which also is preferably of the push button type. The switch 30 is preferably located at a point remote from the bank or other establishment, 50 as in a police station.

In use, when the switch 28 is closed, electric 55 current flows through the switch 19 and energizes the motor 16, rotating the cam 18 a fraction of a revolution to permit the shaft 12 and the yokes 13 and 14 to drop, thus permitting the clutches 9 and 4 to move to operative position. The clutch 9 engages the clutch 4 and said clutch 4 engages the clutch 60 11, thus locking the revolving door 1. Immediately after this occurs, the cam 27 engages the cam 24 and shifts the shaft 21 in a manner to open the switch 19 and simultaneously to close the switch 20, thus breaking 65 the flow of electric current to the motor 16.

Of course, so long as the switch 28 is closed, the signal 29 is energized.

To unlock the door, the switch 30 must be closed at which time electric current will flow through the switch 20 to the motor 16, thereby energizing and actuating said motor. The cam 18 then raises the shaft 12 to lift the clutches 9 and 4 to inoperative position through the medium of the yokes 14 and 13, respectively. The cam 27 then engages the 70 arm 25 and shifts the shaft 21 in an opposite direction for opening the switch 20 and again closing the switch 19. When the switch 20 is opened, the flow of current to the motor 16 is again interrupted. The switches 19 and 20 are mounted on suitable supports 31 and 32, respectively.

It is believed that the many advantages of a door lock constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A door lock comprising a shaft fixed to the door for rotation therewith, a clutch mounted on the shaft for rotation with said shaft, a clutch engageable with the first named clutch for retaining said first named clutch against rotation, an electric motor, and means operatively connecting one of the clutches to the electric motor for actuation thereby, said means including a cam mounted on the motor shaft, a slidably mounted shaft, an arm fixed on the slidable shaft and engageable by the cam for actuation thereby, and a yoke operatively connecting said one clutch to the slidable shaft for actuation thereby.

2. A door lock comprising a shaft fixed to the door for rotation therewith, a stationary clutch encircling the shaft, a double clutch splined on the shaft and engageable, at one end, with the stationary clutch, a slidably mounted clutch engageable with the double clutch for retaining the same against rotation, an electric motor, and means operatively connecting the second and third named clutches to the electric motor for actuation to inoperative position thereby.

3. A door lock comprising a shaft fixed to the door for rotation therewith, a stationary clutch encircling the shaft, a double clutch splined on the shaft and engageable, at one end, with the stationary clutch, a slidably mounted clutch engageable with the double clutch for retaining the same against rotation, an electric motor, and means operatively connecting the second and third named clutches to the electric motor for actuation to inoperative position thereby, said means includ-

ing a cam mounted on the motor shaft, a slide-
able shaft, an arm fixed on the slideable shaft
and engageable with the cam for actuation
thereby, and yokes fixed on the slideable shaft
5 and engaged with said second and third
named clutches for connecting the same to
the slideable shaft for actuation thereby.

In testimony whereof we affix our signa-
tures.

10 WILLIAM V. PARR.
CHARLES A. LOVE.
JOHN J. BARNES.
